UNITED STATES PATENT OFFICE

CHARLES M. CLARK, OF SUMMIT, NEW JERSEY, ASSIGNOR OF ONE-HALF
TO HENRY M. HARDING, OF NEW YORK, N. Y.

SINGLE-PILOT-WIRE CONTROL SYSTEM.

No. 829,139.

Specification of Letters Patent.

Patented Aug. 21, 1906.

Application filed May 16, 1906. Serial No. 317,234.

To all whom it may concern:

Be it known that I, CHARLES M. CLARK, a citizen of the United States, residing at Summit, in the county of Union and State of New Jersey, have invented certain new and useful Improvements in Single-Pilot-Wire Control Systems, of which the following is a full, clear, and exact description.

My invention relates to an electric circuit or system for controlling machines or devices at a distance or any desired point.

The main object of the invention is to secure complete control by means of a single wire.

15 A specific field of utility for my invention lies in the multiple-unit control of trains, in which the motors upon each of the cars are called upon to operate at varying speeds and reverse under the control of a single master-controller operating through a pilot-circuit. The invention has equal utility, however, for the control of elevators, mining-locomotives, signal systems, and the governing of all kinds of machinery at a distant point.

25 With these and other objects in view my invention consists in the construction, combination, in the location, and in the arrangement of circuits and parts, as hereinafter set forth and shown, and finally particularly 30 pointed out in the appended claims.

The drawing shows diagrammatically a control system embodying the principles of my invention.

Practically all electrical machinery is now 35 operated from a power-circuit of fixed voltage, generally five hundred volts, which supplies the motors in any convenient way. In the case of trains the electric power is supplied through the rails and the trolley, which 40 are maintained at the predetermined potential difference required. The control of the electrically-operated machinery is accomplished by switches, rheostats, contactors, and various other controlling apparatus 45 which is supplied for the purpose upon the market. The well-known contactors used on all electric trains are an example of controlling means for an electric motor which are set into operation by a pilot-operating 50 circuit. These features form no part of my present invention and are well understood by those skilled in the art, and I therefore have confined the present description to the mere

establishment of separate circuits which, it will be understood, are employed with contactors or other instruments or devices for governing and operating electrical machinery. It is to be understood that the present invention relates only to the circuit and parts extending to the master-controller and by means of which various line devices or circuits are actuated at will and over a single wire from the master-controller.

In the drawing, 1 and 2 indicate wires or metallic elements forming part of a power-circuit and maintained at a fixed or alternating difference of potential. The wires 1 and 2 may be respectively the trolley and the track-rails of a railway system having cars A and B. 3 indicates a wire or circuit which is included in each car of the train and which is connected to a form of controller at the point 3'. 4 denotes the pilot-wire, which is connected between the several cars at the points 4', so as to form a continuous circuit throughout the train. 4" indicates branch connections from the pilot-wire to points 3' on the wire 3 adjacent to the controllers. At points 7 on the extremity of the circuits 3 on each of the cars I tap resistance connections 5 and 6 to the power-terminals. The resistances 5 and 6 may be motors, lamps, magnets, heaters, or other convenient elements of about equal ohmic value. In some cases when my invention is employed with alternating-current 85 circuits the resistances 5 and 6 will be substituted by inductance-coils of about equal impedance. In this way the circuit 3 on each of the cars extends between a point tapped by resistance connections to both power-terminals and is extended to controllers shown at the other end of the car. In practice there would of course be two controllers on each car. Between the connections 7 and the part 3' of the pilot-circuit may be any number of 90 controlling devices, depending on the requirements of any particular system or installation.

At each station, section, or car I provide a number of what I shall term "governing-relays" 10, 11, 12, 13, and 14. Each of these governing-relays includes a winding through which the current in wire 3 passes and by means of which the governing-relay is made to operate at a certain position of the master-controller. As illustrated, the governing-

relays 11, 12, 13, and 14 have a closed magnetic circuit or ring, the two halves of which are wound with separate coils 15 and 16. The coils 16 are in a local circuit through which current constantly passes, which is conveniently attained by connecting the coils in series between the wires or power-terminals 1 and 2. The various coils 15 are arranged to be traversed by the current in the wire 3. The coils of governing-relays 11 and 12 are in series with one another, while the coils of relays 13 and 14 are in parallel. In the drawing the coils 15 of relays 13 and 14 are in the opposite direction to the coils of relays 11 and 12. The governing-relay 10 is of different form, being merely a solenoid-coil 17, attracting an armature 18, which moves a pointer 19 over contacts 20. The contacts 20 may be connected to contactors, if desired, by electrical connections, which it is not necessary to show, or they may be connected to any separate instruments, valves, or devices for securing the government of electrical apparatus or the transmission of signals. In like manner each of the governing-relays 11, 12, 13, and 14 may operate any desired contactors or devices. For this purpose I have illustrated armatures 21 moving against contact-points 22 when attracted by the magnets in opposition to their spring 23. Each controller has an arm 24, which moves over resistance-contacts 25 and 26. The final contacts of the respective series are connected to the wires or power elements 1 and 2.

The operation is as follows: Supposing it is desired to operate a certain mechanism at stations A and B from the forward controller, I will suppose that the mechanism is the first contactor of the car-motors which is connected to run said motors in a forward direction. I will imagine this particular contactor to be connected so as to operate when the governing-relay 12 attracts its armature 21 against the contact-point 22. For this purpose the motorman moves arm 24 downward to the first notch of resistance-contacts 26. Under these circumstances a light current passes through each of the resistances 5 from the power-terminal 1 and through each 50 of the wires or circuits 3 on the respective cars. From there the current passes through the connections 4" into the pilot-wire and through the controller resistance 26 into the other branch 2 of the power connections. In traversing this circuit the current flows through the coils 17 and 15 of the various governing-relays. If the power-terminals 1 and 2 are alternating-current terminals, the currents will traverse the above circuit in alternating directions. In the meantime all of the coils 16 are constantly connected to the power-terminals, so that a current is passing through them which either acts in conjunction with or in opposition to the current of the coils 15. If the coils 15 and 16

act in conjunction, a closed magnetic circuit is formed by the core of the governing-relay. Under these circumstances no pole is developed no matter how great the intensity of the current may be. If, however, the cores 15 and 16 act in opposition to one another, a pair of poles are produced which may be symmetrical and quite intense if the magneto-motive forces of the two coils are about balanced.

All of the governing-relays are differently constructed, and in the arrangement illustrated the coils of governing-relays 11 and 12 act in opposition to one another, so that poles are produced; but the coils of relays 13 and 14 act in conjunction, so that no pole is developed no matter how strong the current may be. This is true in each case whether the power-mains 1 and 2 are energized with direct or alternating current. If an alternating current is employed, the successive alternations affect all the coils of all the relays, so that the conjunctive or opposition effect thereof is the same as with a direct current. The governing-relays 11 and 12 are supposed to be wound differently, so that for a certain intensity of current their magneto-motive forces are different. For a certain position of the controller-arm 24 a certain intensity of current will flow, and in the position shown I will assume that this current produces magneto-motive forces in the coils 15 and 16 of relay 12, which balance one another. A symmetrical pole will therefore be developed and the armature 21 attracted against stop 22 to close any desired local circuit. This may be the usual circuit for closing one contactor of a series which effects the control of the car-motor. As the control-arm 24 is moved to a new position the magneto-motive force of all the coils 15 increases, and at a certain position the magneto-motive forces of coils 15 and 16 of relay 11 balance, so that armature 21 of this relay is attracted and a second contactor operated.

As many governing-relays may be used as are necessary, and it is evident that they will be successively operated as above described. As the successive relays operate the relays previously operated may or may not continue to attract their armatures. In the case of train control it is immaterial whether or not the relays previously actuated continue to attract their armatures. When the controller-arm 24 is moved upward, the relays 13 and 14 operate for different amounts of throw in the same way as the relays 11 and 12. Thus any one of the relays 11, 12, 13, and 14 may be separately actuated by the movement of the controller-arm 24, and all through a single-pilot-wire connection. It is obvious that the number of relays may be made as great as is desired. One set operates for upward throw of arm 24, the other set on downward throw. This follows be-

cause the direction of winding of coils 15 of relays 13 and 14 is opposite to that of the corresponding coils of relays 11 and 12. When the arm 24 is moved upward, the current passes from trolley-wire 1 through resistance 25, through arm 24, and through the coils 15 in one direction, and when arm 24 is moved downward the current passes from conductor 1, through resistance 5, and 10 through the coils 15 in the opposite direction. Accordingly since these relays respond only to currents in one direction, it happens that relays 11 and 12 respond when the arm 24 moves in one direction, while relays 13 and 15 14 respond when arm 24 moves in the other direction.

The relays 10 are illustrative of the control which is obtainable by varying the strength of the pilot-current. These relays 10 may 20 be used in conjunction with one or more relays of the form 11, 12, 13, and 14. For example, one or more of the relays 11 12 13 14 may be used to control the direction of movement of the motors, while the relays 10 may 25 be employed to regulate the speed of the motors.

The gist of the invention lies in the dividing of the operating voltage by a pair of resistances and tapping a special circuit-wire 30 at an intermediate point, so as to get any range of current strength in the wire by a master-controller. With this is combined governing-relays of such a type as to be responsive to different current conditions, and 35 thereby actuate any predetermined or selected local devices or instruments.

What I claim is—

1. In a control system, a plurality of governing-relays in a special circuit, resistance 40 connections from the power- terminals to such circuit, and variable connections at an other point of the circuit for controlling the strength of current therein.

2. A control system having a single pilot- 45 wire, governing-relays in special circuits having resistance connections with the power- terminals, and means connected to the pilot-wire for varying the intensity of current in said circuits.

50 3. In a control system, a plurality of governing-relays having coils in a special circuit, and additional coils in a constantly-energized circuit, said coils acting in a closed magnetic circuit, a pilot-wire connected to said special circuit, and means for connecting said pilot-wire to either power-terminal,

whereby a pole is produced in any desired governing-relay.

4. In a control system, a pair of power wires or terminals, a special circuit-wire connected thereto by resistances so as to normally have an intermediate potential, a master-controller for connecting said circuit-wire to either of said power-wires, and governing-relays in said circuit. 60

5. In a control system, a pair of power wires or terminals, a special circuit-wire connected thereto by resistances so as to normally have an intermediate potential, a master-controller for connecting said circuit-wire to either of said power-wires, and governing-relays in said circuit-wire responsive to currents of a varying phase or direction in said circuit. 70

6. In a control system, a pair of power wires or terminals, a pilot-wire connected thereto by resistances so as to normally have an intermediate potential, a master-controller for connecting said pilot-wire to either of said power-wires, and governing-relays responsive to currents of only one direction 80 and predetermined strength in said pilot-circuit.

7. In a control system, a pair of power wires or terminals, a pilot-wire connected 85 thereto by resistances so as to normally have an intermediate potential, a master-controller for connecting said pilot-wire to either of said power-wires, and governing-relays responsive to currents of predetermined 90 strength only in said pilot-circuit.

8. In a control system, a pilot-wire circuit, a governing-relay having a closed magnetic circuit and two coils thereon, one of said coils being constantly energized and the 95 other coil being included in the pilot-circuit.

9. In a control system, a pilot-wire circuit, a plurality of governing-relays each having a closed magnetic circuit and two coils thereon one of which is constantly energized from the power-circuit, and the other included in said pilot-circuit, the different relays being wound and adjusted to respond to currents of different strengths and characters in said pilot-circuit. 100 105

In witness whereof I subscribe my signature in the presence of two witnesses.
